UNITED STATES PATENT OFFICE.

HARRY P. MACDONALD, OF MONTCLAIR, NEW JERSEY, ASSIGNOR TO THE SNEAD & CO.
IRON WORKS, OF JERSEY CITY, NEW JERSEY, A CORPORATION OF NEW JERSEY.

ROLL RAMMING APPARATUS.

1,076,683.

Specification of Letters Patent.

Patented Oct. 28, 1913.

Application filed June 28, 1913. Serial No. 776,302.

To all whom it may concern:

Be it known that I, HARRY P. MACDONALD, a citizen of the United States, residing at Montclair, in the county of Essex and State of New Jersey, have invented certain new and useful Improvements in Roll Ramming Apparatus, of which the following is a specification:

This invention relates to roll ramming apparatus and has reference primarily to the provision of improved control means for actuating the mechanism operating the roll.

A further object of the invention resides in the provision of novel and improved means whereby it is impossible to actuate the ramming roll until all parts are in operative position.

My invention also contemplates the provision of means whereby the control mechanism is automatically made inoperative when the tracks for supporting the roll are moved to inoperative position and whereby it is made impossible to move one of the tracks to inoperative position without also moving the other track to such position.

The foregoing, together with such other objects as may hereinafter appear or are incident to my invention I attain by means of a construction which I have illustrated in preferred form in the accompanying drawings wherein:

Figure 1 is a plan view of a roll ramming machine, partially broken away, showing my improved apparatus; Fig. 2 is a partial side elevation and section of Figure 1; and Fig. 3 is a sectional view showing a detail of the invention.

This invention is primarily designed for use in connection with roll ramming apparatus. The general construction of the roll ramming mechanism proper is of the usual type and is illustrated diagrammatically in the drawings. In brief, the apparatus comprises a frame 7 adapted to contain any suitable form of pattern drawing mechanism, above which is supported the usual flask 8. Hinged to the frame 7 by means of hinge members 9 are tracks 10 and 10^a which, when moved to operative position, rest upon the top face of the flask and when moved to inoperative position, lie to the side of the frame 7 clear of the flask, so that the latter can be readily removed. The ramming roll 11 is mounted in a framework 12 and is provided with grooves or gutters 13 at each end

into which the vertical legs of the tracks 10 and 10^a extend. By this construction, when the ramming roll is advanced or retracted, the tracks 10 and 10^a are prevented from spreading apart. Adjacent the inner end of the frame 7 is a second framework 14 which is provided with tracks 10' with which tracks 10 and 10^a align when the latter are moved to operative position. The ramming roll 11 is supported on the tracks 10' when inoperative position.

Referring now to those features of my invention which depart from the usual construction, it will be seen that the ramming roll is operated by means of a rack 15 which is secured to the framework 12 and is engaged by a pinion 16 mounted on the main driving shaft 17, such shaft being turned by means of a motor 18 through interposed reduction gearing, the casing of which is indicated by the numeral 19. The motor is controlled by a controller 20 of any preferred type; the reversal of the ramming roll being preferably accomplished by reversing the direction of the current in the motor. 80

In operation it is desirable to have the ramming roll automatically reversed when it reaches extreme forward position, and return it to initial position. This reversal is accomplished by means of an automatic reversing mechanism 21 which is of the same general construction as that illustrated and described in my issued application No. 1,060,848, dated May 6, 1913. The controller is manually operated by means of the hand lever 22 which is mounted for reciprocative movement in brackets 23 and 24 carried by the framework 14. The handle is provided with a rack portion 25 which engages a gear segment 26 mounted on the controller shaft and it will be apparent that reciprocative movement of the handle 22 imparts a rotary movement to the controller shaft through the medium of the gear 26 and rack 25. It is advantageous to automatically lock the lever 22 and thereby prevent accidental actuation of the controller to advance the roll when the tracks 10 are not in proper operative position and to this end I provide the following mechanism.

Pivotedly mounted on the framework 14 is an oscillating lever 27, the pivotal point of support for such lever being so located that the inner end of said lever normally tends to move downward. Secured to the

100

110

forward end of the lever 27 is a pin 28 which lies beneath the track 10 when the latter is in operative position, the end of said pin being engaged by the track, the weight of which serves to depress the forward end of the lever 27. At the rear end the lever 27 is connected by means of the link 29 to a transversely extending rocking lever 30 fulcrumed on the framework 14 as 10 at 31. Secured to the free end of the lever 30 is a vertically extending bracket plate 32 which is adapted to abut against the bracket 24 and serve as a stop for preventing rearward movement of the handle 22. The 15 bracket 32 and the lever 30 are shown in side elevation in Fig. 3. It will be clear that when the track 10 is moved to operative position and depresses the forward end of the lever 27, the rearward end will be elevated, 20 which will cause the rocking lever 30 to depress the plate 32 so that the latter will lie clear of the handle 22. The handle can then be moved to actuate the controller. When the track 10 is swung to inoperative position 25 clear of the flask, the rear end of the lever 27 will fall by the action of gravity as previously pointed out and the rocking lever 30 will elevate the bracket 32 into position indicated in dotted lines in Fig. 2, at which time rearward movement of the handle 22 is automatically prevented. From the foregoing it 30 will be apparent that it is impossible to shift the controller unless the track 10 is in proper operative position, the accidental actuation 35 of the ramming roll being thus prevented and the liability of injury to the mold parts obviated.

The track 10 is provided at its forward end with an operating handle 33 by means of 40 which the track can be readily swung into and out of operative position and the track 10^a is provided with a similar operating handle 34. In order to prevent the operator from moving the track 10^a to inoperative 45 position while the track 10 is still in operative position, the handle 34 is so arranged as to project beneath the track 10. By this construction, it is impossible to raise the handle 34 until the track 10 has first been 50 moved to inoperative position and the handle 22 automatically locked. The construction is simple, the parts may be readily operated and the liability of accidental operation of the ramming roll and consequent 55 injury to the apparatus is reduced to a minimum.

What I claim is:

1. In roll ramming apparatus the combination of a flask, a roll for ramming the 60 sand in the flask, a movable track for supporting the roll above the flask when in operative position and lying free of the flask when in inoperative position, power mechanism for operating the roll, a control for 65 the power mechanism, and means for lock-

ing the control automatically releasing when the track is moved to operative position.

2. In roll ramming apparatus the combination of a flask, a roll for ramming the sand in the flask, a movable track for supporting the roll above the flask when in operative position and lying free of the flask when in inoperative position, power mechanism for operating the roll, a control for the power mechanism, and means automatically moving to lock the control when the track is moved to inoperative position. 70 75

3. In roll ramming apparatus the combination of a flask, a roll for ramming the sand in the flask, a movable track for supporting the roll above the flask when in operative position and lying free of the flask when in inoperative position, and locking means for the roll automatically releasing when the track is moved to operative 80 85 position.

4. In roll ramming apparatus the combination of a flask, a ramming roll, a support for the roll movable into and out of position over the flask, a platform adjacent the flask 90 adapted to support the roll in inoperative position, and means preventing movement of the roll from off the platform, said means automatically releasing when the support is moved into operative position over the 95 flask.

5. In roll ramming apparatus a flask, a roll adapted to ram the sand in the flask, a pair of independently movable tracks for supporting the roll over the flask, and means 100 whereby one of the tracks cannot be moved out of operative position when the other track is in operative position.

6. In roll ramming apparatus a flask, a roll adapted to ram the sand in the flask, a 105 pair of independently movable tracks for supporting the roll over the flask, means whereby the first track cannot be moved out of operative position when the second track is in operative position, and locking means 110 for preventing movement of the roll automatically actuated when the second track is moved out of operative position.

7. In roll ramming apparatus a flask, a roll adapted to ram the sand in the flask, 115 a pair of independently movable tracks for supporting the roll over the flask, and a handle for moving one of the tracks, said handle extending beneath the other track so that the latter must first be moved to 120 inoperative position before the former can be moved to such position.

8. In roll ramming apparatus the combination of a flask, a ramming roll, a movable track adapted when moved to operative position to support the roll over the flask, power means for operating the flask, a control for said power means, a rocking lever and means carried on one end of said lever for locking the control, the other end of said 125 130

lever being engaged by the track when the latter is moved to operative position.

9. In roll ramming apparatus the combination of a flask, a ramming roll, a movable track adapted when moved to operative position to support the roll over the flask, a platform adjacent the flask for supporting the roll when the latter is in inoperative position, power means for operating the roll, a controller for said means, an operating handle for the controller, a lever pivoted in intermediate its ends to the platform, and a

locking device carried on one end of said lever and engaging the said handle, the other end of said lever being engaged and depressed by the track when the latter is moved to operative position. 15

In testimony whereof I have hereunto signed my name in the presence of the two subscribed witnesses.

HARRY P. MACDONALD.
